[57] CLAIM

The ornamental design for an eyeglass earstem, as shown and described.

DESCRIPTION

FIG. 1 is a top perspective view of the eyeglass earstem showing my new design, the eyeglass frame being shown in broken-lines for illustrative purposes only;

FIG. 2 is a front elevational view thereof;

FIG. 3 is a top plan view thereof;

FIG. 4 is an end elevational view thereof;

FIG. 5 is an opposite end elevational view thereof;

FIG. 6 is a rear elevational view thereof.

*Fig. 1**Fig. 3**Fig. 4**Fig. 2**Fig. 5**Fig. 6*
